[57] **ABSTRACT**

The present invention relates to an oxygen tuyere of a steel-melting mill, whose body has pipes for supplying oxygen, a cooling medium and a shielding gas, coaxially arranged therein. The lower portion of the body of the tuyere has nozzles for supplying oxygen into liquid metal and slot-like nozzles for supplying a shielding gas, disposed above the former ones and forming a spiral, at least, a double-turn one, which embraces the body along its periphery.

OXYGEN TOYERE OF A STEEL-MELTING MILL

The invention relates to the field of production of steel by way of blowing oxygen through liquid metal in a steel-melting mill, e.g., a furnace or a converter, and, more particularly, to an oxygen tuyere installed in said mill.

An oxygen tuyere of a steel-melting mill, whose body has pipes for supplying oxygen, a cooling medium and a shielding gas, coaxially arranged therein, is known. The lower portion of this body has nozzles for supplying oxygen into liquid metal, communicated with a duct, along which oxygen is delivered, and nozzles for supplying a shielding gas, arranged above the former nozzles and communicated with the interpipe space along which a shielding gas is delivered. The latter nozzles are made cylindrical, are equidistantly spaced from one another and are arranged along an imaginary circumference along the periphery of the body of the tuyere (cf. British Pat. No. 934,112; Cl. 51(1)b, 1962).

The nozzles supplying a shielding gas create a gas shield intended to decrease the amount of iron oxides ("brown smoke") carried away from the working space of the metallurgical unit, and, therefore, to raise the output of ready metal; to prevent drops of metal and slag from getting onto the ceiling and walls of the steel furnace, and, therefore, to preclude premature damage of the furnace; and to provide for a more complete combustion of carbon oxide separated in the course of the blowing-through, and, consequently, to raise the temperature of the slag and to decrease its foam-formation, which improves the transfer of heat to the metal and prevents the latter from being carried away with the slag being removed.

In the known tuyere, however, this gas shield has a plurality of "ports" whose number depends on the distance between adjacent nozzles. Through these "ports" of the shield carbon oxide penetrates and is carried away from the working space, and drops of the metal and slag get onto the ceiling and walls of the steel furnace.

In the known tuyere the nozzles cannot be brought closer to one another as it is necessary to provide a jacket of the cooling medium around every nozzle, since otherwise the tuyere will burn out.

This contradiction leads to the fact that in the conventional tuyere of a steel-melting mill there is no continuous screen from the shielding gas, which results in all negative consequences following therefrom, and the tuyere proper has a low resistance due to its poor cooling in the zone of disposition of the nozzles for supplying the shielding gas.

Thus, the problem lies in decreasing the number of the "ports" in the gas shield and, at the same time, in taking measures aimed at preventing the worsening of the conditions of the tuyere cooling in the zone of disposition of the nozzles supplying the shielding gas.

An object of the present invention is to provide such an oxygen tuyere of a steel-melting mill, that would create a continuous shielding screen above the liquid metal in the steel-melting mill.

Another object of the present invention is to provide such an oxygen tuyere that would be sufficiently cooled in the zone of disposition of the nozzles supplying a shielding gas.

The afore-said and other objects are accomplished by that the nozzles for supplying a shielding gas are made as slots forming a spiral, at least a double-turn one, which embraces the body of the tuyere along its periphery.

The following description of an exemplary embodiment of the present invention is given with reference to the accompanying drawings, in which:

FIG. 1 shows a longitudinal section of an oxygen tuyere of a steel-melting mill, built according to the present invention;

FIG. 2 is a section taken along line II-II of FIG. 1.

An oxygen tuyere comprises a body 1 (FIGS. 1,2) having pipes 2,3,4 and 5 coaxially arranged therein. Oxygen is supplied into an annular duct 6 between the pipes 2 and 3 along a pipe branch 7, and is blown through nozzles 8 into liquid metal (not shown in the drawing).

A shielding gas (air) is delivered along an annular duct 9 between the pipes 4 and 5 through a pipe branch 10, and is supplied into a furnace (not shown in the drawing) through nozzles arranged in the body above the nozzles 8 and made as slots 11 forming a double-turn spiral embracing the body 1 along the periphery thereof. The slots 11 are disposed with respect to the surface of the liquid metal at an angle of 45° so that, on leaving the slots, the shielding air forms a continuous shielding screen above the zone of the oxygen blowing-through.

To cool the tuyere, a cooling medium (for example, water) is delivered through a pipe branch 12 into an annular clearance 13 between the pipes 3 and 4 and then the pipes 3 and 5, which water is then drained from the tuyere along ducts 14 and the pipe 2, as well as along a duct 15 between the pipe 5 and the body 1, and is then converged in an outlet pipe branch 16.

The above-described design of the nozzles for supplying a shielding air makes it possible to obtain a continuous shielding screen and provides, at the same time, for a reliable cooling of the body 1 at the point of disposition of the slots 11 for supplying a shielding air. The continuous shield is created due to the fact that the slots 11 embrace the whole perimeter of the tuyere, the reliability of the cooling being provided due to the fact that the slots are made as a double-turn helical line. At the same time, due to the great pitch of the spiral, there is provided a sufficiently great cross-sectional area for passage of the water.

To preclude the destruction of the tuyere by the stresses arising in the body 1 during its heating, the tuyere is equipped with two stuffing box devices 17 and 18.

The movement of the water in the tuyere is shown by solid arrows, the movement of the shielding air - by dotted arrows, and the movement of oxygen - by dashed-dotted arrows.

We claim:

1. An oxygen tuyere of a steel-melting mill, comprising a body having pipes for supplying oxygen, a cooling medium and a shielding gas, coaxially arranged therein; nozzles for supplying oxygen into liquid metal, disposed in the lower portion of said body and communicated with a duct along which oxygen is delivered; nozzles for supplying said shielding gas, disposed in said body above said nozzles for supplying said oxygen, made as

slots forming a spiral, at least a double-turn one, which embraces said body along its periphery, and communicated with an inter-pipe space along which said shielding gas is supplied.
